FLOOR WAXER

Rolland Lachapelle, Hull, Quebec, Canada

Application February 9, 1940, Serial No. 318,174

5 Claims. (Cl. 91—39)

My invention relates to waxers for floors of that type wherein a self contained supply of liquid wax feeds the same while it is being operated.

5 The objects of my invention are to provide a waxer of the above-mentioned type which is simple in construction, easy of operation and can be produced and sold at a very low cost.

Other objects of my invention will become apparent in the following description thereof illustrated in the drawing appended thereto and in which:

Figure 1 is a side elevation of the complete waxer.

15 Figure 2 is a vertical section thereof; and,

Figure 3 is a vertical section of the adapter for the wax container.

The invention resides mainly in the novel construction of the device consisting of a rectangular wooden frame 5 provided with a distribution plate 6. Plate 6 has a large number of perforations 7 distributed throughout its area. The assembly of frame 6 and plate 7 surmount a slab of sponge rubber 8 suitably held thereto and wrapped with a piece of nappy cloth or felt 9 of a size which permits the same to cover the outside of the frame as shown. The cloth may be glued or otherwise fastened at its top to the frame but is mainly held around the same by cover 10 which covers the frame and which surrounds the same holding the cloth tightly therebetween.

Fastened to the frame by means of rivets 11 is a bracket 12 having a tubular opening 13 adapted to receive a handle 14 and hold the same at a convenient angle to the assembly already described. Fastened to the handle by suitable means is a sheet metal clamp 15 of resilient nature adapted to receive and hold a container 16. To the mouth of the container is screwed an adapter 17 shown in detail in Figure 3. Adapter 17 is provided with a metering tube 18, passing therethrough, which serves as a nipple for connection with a flexible tube 19 leading to, and passing through an aperture in cover 10. The adapter is further provided with a small vent tube 20 reaching a point adjacent the remote end of the container as shown.

In use a container filled with wax of the liquid type is uncapped and slipped in clamp 15 when the waxer is turned upside down and adapter 17 screwed thereon. The waxer is then turned back to its normal position when the fluid wax will flow lightly through tube 18 and on in tube 19 reaching plate 6 by which it is evenly distributed over the rubber sponge. The sponge becomes impregnated with the wax and conveys

it to the cloth which becomes dampened with it. By sliding the waxer with light pressure on the floor or any other surface to be waxed an even and smooth finish results. In order to prevent the waxer from marring any object with which it may come in contact, a band of rubber 21 is mounted around the cover as shown.

5 What I claim is:

1. A waxer comprising a slab of spongy rubber covered with cloth, a frame over said slab and fastened thereto, a cover over said frame, a handle fastened to said frame, a wax container mounted on said handle and means to convey the wax in said container through said cover to said slab.

15 2. A waxer comprising a slab of spongy rubber covered with a cloth, a frame over said slab and fastened thereto, a cover over said frame, a handle fastened to said frame, a clamp on said handle adapted to hold a fluid container, an adapter for said container comprising a vent and a metering tube, and a flexible tube leading from said metering tube passing through said cover to distribute the fluid over said slab.

25 3. A waxer comprising a slab of spongy rubber covered with a cloth, a frame over said slab fastened thereto, a perforated distributing plate in said frame adjacent said slab, a cover over said frame, a handle fastened to said frame, a wax container mounted on said handle and means to convey the wax in said container through said cover to said slab.

30 4. A waxer comprising a slab of spongy rubber covered with a cloth, a frame over said slab, a perforated distribution plate in said frame adjacent said slab, a cover over said frame, a handle fastened to said frame, a clamp on said handle adapted to hold a fluid container, an adapter for said container comprising a vent and a metering tube, and a flexible tube leading from said metering tube passing through said cover to distribute the fluid over said slab.

35 5. A waxer comprising a slab of spongy rubber, a frame superposed over said slab, a cloth cover underneath said slab extending along the sides of said slab and frame, a cover over said frame having a rim extending over said cloth on sides of said frame, a handle fastened to said frame, a clamp on said handle adapted to hold a fluid container, an adapter for said container comprising a vent and a metering tube, and a flexible tube leading from said metering tube passing through said cover to distribute the fluid over said slab.
